US0D1050799S

(12) **United States Design Patent** (10) Patent No.: **US D1,050,799 S**
(45) Date of Patent: ** Nov. 12, 2024

(54) **IMMERSION BLENDER**

(71) Applicant: **SharkNinja Operating LLC**,
Needham, MA (US)

(72) Inventors: **Da Deng**, Newton, MA (US); **Trevor Patrick Dyment**, Boston, MA (US);
Noah William Weinstock, Boston, MA (US)

(73) Assignee: **SharkNinja Operating LLC**,
Needham, MA (US)

(**) Term: **15 Years**

(21) Appl. No.: **29/845,570**

(22) Filed: **Jul. 8, 2022**

(51) LOC (14) Cl. **31-00**

(52) U.S. Cl. **D7/380**
